NELSON J. GREENISON, OF NEW YORK, N. Y.

SHOE-SHINING STAND.

1,328,667.

Specification of Letters Patent. Patented Jan. 20, 1920.

Application filed May 21, 1919. Serial No. 293,599.

To all whom it may concern:

Be it known that I, NELSON J. GREENISON, a citizen of the United States, and a resident of the city of New York, borough of the Bronx, in the county of Bronx and State of New York, have invented a new and Improved Shoe-Shining Stand, of which the following is a full, clear, and exact description.

10 The present invention relates to new and useful improvements in shoe-shining stands, and pertains more particularly to a foot-rest for devices of this character.

15 The primary object of the invention is to provide a shoe-shining stand in which the foot-rest is adapted for folding within a suitable receptacle or box-like structure, and, at the same time, provide necessary space for the storing of shoe-shining articles, such 20 as brushes, paste, polishing cloths, etc.

Reference is to be had to the accompanying drawings in which similar characters of reference indicate corresponding parts in all the views, and in which—

25 Figure 1 is a top plan view of a shoe-shining stand showing the lid in its open position;

Fig. 2 is a vertical sectional view on the line 2—2 of Fig. 1;

30 Fig. 3 is a vertical sectional view on the line 3—3 of Fig. 1;

Fig. 4 is a fragmentary view of a modified form of the invention.

Referring more specifically to the drawings, the reference character 5 designates a box-like structure or receptacle, which receptacle is provided at each corner thereof with a supporting leg 6. These supporting legs 6 may be of any desired height, and 40 the receptacle may be provided with a suitable hinged cover 7 secured thereto in any desired manner. The reference character 8 designates a foot-rest and the same comprises the conventional shoe-shaped body- 45 portion, from the opposite ends of which depend legs 9 by which the foot-rest is supported in its operative position.

Each of the legs 9 is provided near its lower end with a curved slot 10, which passes 50 into said leg from one of the side edges thereof, and projecting longitudinally of each of the legs from its bottom end, is a slot 11. The slots 10 and 11 are adapted to receive studs 12 and 13, respectively, as 55 shown in Figs. 2 and 3. The studs 13 form the pivot points of the legs 9, while the studs

12 engage in the curved slots 10 to lock said legs against movement about their pivot points.

When it is desired to use the foot-rest, the 60 same is moved to the position shown in the drawings, in which position the curved slot 10 of each of the legs 9 engages its respective stud 12 for preventing movement of the legs about their pivot points 13. 65

When it is desired to return the parts to the position occupied when the device is not in use, the foot-rest 8 is grasped and moved vertically about the studs 13 until the curved slots 10 disengage the studs 12. When the 70 curved slots 10 have disengaged the studs 12, it will be seen that the stand is free to move about the studs 13, to permit of the foot-rest 8 folding downwardly into the box-like receptacle 5. 75

In the modified form of the invention shown in Fig. 4, the elongated slot 11 is open at its lower end, and for the purpose of closing the lower end of said slot, a transversely extending bolt 15 is employed, said 80 bolt having screw-threaded engagement as at 16, with one of the side walls 17 of the slot.

To prevent sliding movement of the device relatively of its pivot point, a cotter pin 85 or similar device 18 is employed, and by removing said cotter pin 18, the device is free to be moved to its folded position or removed entirely.

While the present invention is shown as 90 applied to a shoe-blacking stand, it will be obvious that the same principle of operation is readily applicable to any type of hinged device wherein it is desired to swing the same about a common pivotal point, and 95 then secure the same against movement about its pivotal point to retain it in its operative position, such, for example, as carriage and wagon steps or the like.

From the foregoing it will be apparent 100 that the present invention provides a neat appearing shoe-shining stand in which the foot-rest may be moved to a position where it rests within the box-like receptacle of the stand, and by the construction shown the 105 necessary height may be obtained to bring the foot-rest to the proper operating position without making the legs which support the box-like structure of too great a length.

Having thus described the invention, what 110 is claimed as new is:

In a shoe-shining stand, a suitable re-

ceptacle, a pair of studs arranged in spaced relation to each other on each side of said receptacle, a foot-supporting stand, and depending legs formed integral with said foot-
5 supporting stand, each of said legs having a straight slot projecting inwardly of the body portion from the free end thereof and adapted to receive one of each pair of the aforementioned studs, means for closing the lower
10 end of each of said slots, means extending transversely of each of said slots near its

upper end and coacting with its respective stud to prevent vertical movement of said legs, and a curved slot projecting inwardly of the body portion from the side edge 15 thereof and adapted to receive the other stud of each pair to prevent movement of the legs of the foot-supporting stand about the first-mentioned studs, substantially as described.

NELSON J. GREENISON.
